UNITED STATES PATENT OFFICE

CHARLES DAVID BONSALL, OF PITTSBURGH, PENNSYLVANIA, ASSIGNOR TO P. H. MURPHY COMPANY, OF NEW KENSINGTON, PENNSYLVANIA, A CORPORATION OF PENNSYLVANIA

CAR ROOF

Application filed February 26, 1931. Serial No. 518,432.

This invention relates to car roofs of the type wherein the roof sheets are arranged in upper and lower panels secured in such manner as to act after the manner of a beam supported on the side plates of the car. Its principal objects are to devise a roof of this type that will be strong, simple and permit the use of plain sheets of various widths and thicknesses. It consists in the arrangements and combinations of parts hereinafter described and claimed.

In the accompanying drawings wherein like numerals refer to like parts wherever they occur,

Fig. 1 is a plan view of a portion of a car roof embodying my invention,

Fig. 2 is an enlarged vertical transverse cross-section through one-half of the roof, the section being taken through one of the upper panels on the line 2—2 in Fig. 2.

Fig. 3 is a similar cross-section taken through one of the lower panels of the roof on the line 3—3 in Fig. 1.

Fig. 4 is a vertical longitudinal cross-section through the roof on the line 4—4 in Fig. 1,

Fig. 5 is an enlarged detail cross-sectional view showing the manner of connecting the marginal portions of plain sheets and the channeled sheets together and to the hollow reinforcing member,

Fig. 6 is a vertical longitudinal section through a modified roof construction provided with a strut that connects adjacent car-lines and constitutes a load-lifting beam; and

Fig. 7 is a vertical cross-section on the line 7—7 in Fig. 6.

In the present construction, the roof comprises a series of channel-shaped metal sheets 1 that are spaced apart and extend from side plate to side plate 2 of the car and are riveted or otherwise secured thereto. Along the upstanding sides of such channel-shaped sheets are laterally extending flanges 3 which are lapped by the margins of plain sheets 4 disposed at a higher level than the body portions of the channel-shaped sheets; and the ends of said plain sheets are secured to the side plates of the car. Underneath each lat-

eral flange of the channel-shaped roof sheets is a lateral flange 5 at the top of one side wall of a channel-shaped reinforcing member 6, whose other side wall has a similar flange 7 abutting against the underside of the plain sheet. Each reinforcing member is rigidly secured to adjacent roof sheets by welding or preferably by a series of rivets 8 extending vertically through one of its flanges and the lapped margins of adjacent sheets and by a second row or series of rivets 9 extending vertically through its other flange and the body portion of the plain roof sheet.

The roof sheets arranged and joined together as above described may be considered as a series of hollow ribs open at the bottom alternating with a series of channels open at the top, the ribs corresponding with the plain sheets and the channels corresponding with the channel-shaped sheets. The hollow reinforcing members extend from side plate to side plate and, together with the portions of the roof sheet above them, function after the manner of hollow box girder carlines; and it is noted that such reinforcing members are all located in the hollow ribs of the roof, that is, underneath the plain sheets, and are mainly or wholly between the upper and lower levels of the roof sheets.

As only alternate sheets are pressed or flanged, there is no need for fitting or adjustment or special accuracy in positioning any of the sheets; the only requirement in these respects which the plain sheets have to satisfy is that they must be of proper width to span the space between the channel-shaped sheets and lap the flanges thereof. Thus, it becomes feasible to vary the spacing of the channel-shaped sheets over a considerable range. This is an advantage in connection with new cars because it affords the designer considerable freedom in conforming his construction to his calculations of stresses or to limitations imposed by features of the framework of the car. For instance, it permits the use of narrower plain sheets and consequently more reinforcing members near the middle of the car where the stresses are higher than at the ends of the car, or wider than normal sheets at the middle of the car

or elsewhere if desired. Likewise, it permits the use of thicker plain sheets at the middle than at the end of the car or thicker sheets at one level (usually the upper) than at the other. Likewise, it facilitates repair of the roof away from the home shops by making it practicable to use channel-shaped sheets of any width in cases where channel-shaped sheets of desired width may not be available. It is also noted as a particular advantage of having the reinforcing ribs under the upper panels, which function as compression members of the roof considered as a beam, that the body portions of the channel-shaped sheets become tension members and may, therefore, be wider than would ordinarily be permissible for compression members of the same width and thickness therewith.

20 The construction shown in Figs. 6 and 7 is similar to the construction hereinbefore described, with the addition of members 10 located below the plain sheets with their ends secured to adjacent hollow ribs. These members serve as struts to stiffen the roof and are made of such shape or otherwise adapted to serve as lifting beams to which lifting tackle or devices may be secured. Preferably such members are made in the form of 30 an inverted channel with lateral flanges or ribs adapted to be engaged by slid able tongs or similar devices.

What I claim is:

1. A car roof comprising roof sheets arranged to form panels at different levels with their side edges secured together, the distance between the upper and lower panels being such as to develop substantial beam action in said sheets and separate seam reinforcing members secured to the underside of the upper sheets and substantially between the upper and lower levels of the sheets.

2. A car roof comprising roof sheets arranged to form panels at different levels with their side edges secured together, the distance between the upper and lower panels being such as to develop substantial beam action in said sheets and hollow seam reinforcing members secured to the underside of the upper sheets and substantially between the upper and lower levels of the sheets.

3. A car roof comprising a series of substantially plain sheets alternating with a series of sheets with raised side margins that underlap the side margins of said first mentioned sheets, and separate channel-shaped members with one side margin underlapping and rigidly secured to the lapped margins of said sheets and with the other margin secured flatwise to the underside of said plain sheets.

4. A car roof comprising sheets with raised side margins having lateral flanges and substantially plain sheets alternating with and overlapping said flanges, and channel-shaped members underneath the upper

sheets, said members having side margins underlapping and riveted to the lapped edges of the roof sheets and side flanges riveted to the upper sheets.

5. A car roof comprising a series of substantially plain sheets alternating with a series of sheets with raised side margins having flanges that underlap the side margins of said first mentioned sheets, and channel-shaped members with lateral flanges one of which underlaps and is rigidly secured to the lapped margins of said sheets and the other flange is secured flatwise to the underside of said first mentioned sheets, said channel-shaped members being mainly between the levels of the body portions of the sheets of the two series.

6. A car roof comprising sheets with raised side margins and substantially plain sheets alternating with and overlapping the raised margins of said first mentioned sheets, and a plurality of reinforcing members underneath and secured to the plain sheets.

7. A car roof comprising roof sheets arranged at different levels with their side edges secured together, separate seam reinforcing members secured to the underside of the upper sheets and substantially between the upper and lower levels of the sheets, and members connecting the reinforcing members beneath the respective upper sheets and adapted to strengthen the roof and constitute load-lifting beams.

8. A car roof comprising roof sheets arranged to form panels at different levels with their side edges secured together, the distance between the upper and lower panels being such as to develop substantial beam action in said sheets, separate seam reinforcing members secured to the underside of the upper sheets and substantially between the upper and lower levels of the sheets, and members located substantially between said levels and connecting the reinforcing members beneath the respective upper sheets and adapted to strengthen the roof and constitute load-lifting beams.

9. A car roof comprising roof sheets arranged at different levels with their side edges secured together, separate seam reinforcing members secured to the underside of the upper sheets and substantially between the upper and lower levels of the sheets, and strut members of inverted channel-shape located between said levels and connecting the reinforcing members beneath the respective upper sheets and adapted to strengthen the roof and constitute load-lifting beams.

10. A car roof comprising roof sheets arranged at different levels with their side edges secured together, separate seam reinforcing members secured to the underside of the upper sheets and substantially between the upper and lower levels of the sheets, and strut mem-

bers connecting the respective reinforcing members beneath the respective upper sheets, said strut members being located substantially between said levels and being of inverted channel-shape with lateral flanges.

5 11. A car roof comprising roof sheets secured together along their adjacent margins by hollow box seams, said roof having hollow ribs alternating with channels, and a plurality of separate reinforcing members located beneath and rigidly secured to each of said hollow ribs.

10 12. A car roof comprising roof sheets secured together along their adjacent margins, said roof having hollow ribs alternating with channels, a plurality of separate reinforcing members located beneath and rigidly secured to each of said hollow ribs, and members connecting the reinforcing members beneath said 15 ribs and adapted to strengthen the roof and constitute load-lifting beams.

15 13. A car roof comprising roof sheets secured together along their adjacent margins, said roof having hollow ribs alternating with channels, a plurality of separate reinforcing members located beneath and rigidly secured to each of said hollow ribs, and members connecting the reinforcing members beneath 20 said ribs and adapted to strengthen the roof and constitute load-lifting beams, said reinforcing members and said connecting members being located within said hollow ribs substantially between the tops thereof and the bottoms of said channels.

25 14. A car roof comprising roof sheets secured together along their adjacent margins, said roof having hollow ribs alternating with channels, and members located within said 30 hollow ribs and extending transversely thereof and adapted to strengthen the roof and constitute load-lifting beams.

35 Signed at New Kensington, Pennsylvania,
this 23rd day of Feb., 1931.

CHARLES DAVID BONSALL.
